JESSE WARRINGTON HAYES AND ALMA B. HAYES, OF TAKOMA PARK, MARYLAND

COMBINED CONTAINER AND LAMP-SHADE

Application filed November 22, 1929. Serial No. 408,992.

The invention has for its object to provide a novel and useful combined lamp shade and container for fragile articles, such as and more particularly for electric light bulbs; 5 said container to be made of paper, light cardboard, parchment, or any suitable material, either plain or decorated as may best suit the purpose of the manufacturer.

The device, being made of a single sheet 10 of material, and having a series of scored lines, upon which it is folded, forms without gluing, pasting or fastening by any other means, a perfect box-shaped container. The 15 container may be shipped flat or knocked down and may be easily and readily applied to the light bulb or article to be packed, its simple construction and easy application reducing the cost of manufacture and handling to a minimum.

It is a well appreciated fact that the usual receptacle as provided for electric light bulbs and other fragile articles is discarded as a worthless wrapper when it reaches the ultimate consumer.

It is now an object of our invention to provide a container which may continue its life of usefulness by being converted into a lamp shade, this act of conversion being accomplished by the simple operation of removing the container from the outside wrapper and permitting the corners to flare of their own resiliency, or aided by the hand if necessary. The container thus released from the wrapper forms itself naturally into a shade and may be attached to the fixture by the ordinary means of screwing the bulb into the light socket, it not being necessary to remove the bulb from the aperture which 40 has engaged it in the container.

The shade feature of our device, adding usefulness and attractiveness without increasing the cost of manufacture, will greatly advance the sale of that particular make of 45 electric light bulb whose manufacturer uses this medium of advertising.

While our invention relates specifically to a combined container and shade its possibilities as a container, without giving consideration to the shade feature, should make it exceptionally valuable because of its simple con-

struction and unusual protective features. When made of cheap paper its cost should be lower than that of other devices for similar purposes.

Our invention has a further advantage in 55 being marketable as a lamp shade, without giving consideration to the container feature. The wide range of materials and decorations together with the low cost of the operations involved in its manufacture and 60 handling should make it both popular and profitable.

The various features of our invention are 65 fully set forth in the description of the accompanying drawings making a part of this specification, in which—

Figure 1 is a top plan view of the electric light bulb container encased in an outside wrapper.

Figure 2 is a bottom plan view, showing 70 the electric light bulb engaged and protected by the cushioned corners of the container.

Figure 3 is an exploded view, showing the container, with attached bulb, removed from the outside wrapper and flared to form a 75 shade.

Figure 4 is an elevation of a sheet, of do- 80 decagon shape, scored to fold on certain lines.

In carrying out our invention there is provided a sheet of dodecagon form, as shown 85 in Fig. 4, the size of which sheet may vary according to the size of the article to be packed. While we have shown a dodecagon shape of pattern of plain edge, we would not limit ourselves strictly to this form, as the outer edge may be cut in various designs of rounded or pointed scallops or otherwise when desired for decorative purposes. The sheet is scored on the reverse side to fold on lines 2—2, 3—3, 4—4, and 5—5, thereby 90 forming the four rectangular sides A and the end section B. The sheet is further scored on the obverse side to fold on lines 6—7, and 6—8, which together with the scored lines already described form the corner 95 sections designated as C, D, and E. The hole 1 in the center of the end section B is for the purpose of admitting the neck of the electric bulb as illustrated in Fig. 1.

Figure 1 is a top plan view showing the 100

end section B as already described in Fig. 4, but now encased in outside wrapper H. It further shows the neck of light bulb, F, inserted in hole 1.

Figure 2 is a view of the lower end of the container showing the cushions formed by the surfaces C, D, and E; the surfaces C and E folding inward and lying substantially parallel with the walls of the container; the surfaces D lying across the corners and against the bulb G, hugging it and protecting it against breakage in handling. K represents the open spaces formed by the surfaces C, D, and E, giving greater resiliency to the cushions. The wrapper H confines the container, holding it securely in box form.

In the exploded view, reference being had to Fig. 3, the container with the light bulb has been removed from wrapper H. In this side elevation the corners formed by folding on scored lines 6—7, and 6—8, defining sections C, D, and E, as described in Fig. 4, are permitted to flare, due to the resiliency of the paper, and thereby form a lamp shade. A wider flare of the shade may be effected by the hand if desired. Lines 2 and 3 are parts of the lines 2—2, and 3—3, as shown on the flat surface of Fig. 4. These lines together with the lines 4—4, 6—7, and 6—8, divide the figure into the several sections designated as A, C, D, and E. The electric bulb G is shown within the shade and ready to be connected with the electric circuit by the usual means of screwing the neck F into the light socket, without removing the bulb from its original position in the container. The wrapper H, reference still being had to Fig. 3, is made of one sheet, two edges of which are brought together and made fast by gluing or by other means. Its adaptation to our use is also shown in Figures 1 and 2. While the wrapper herein described—a wrapper of sufficient length to extend beyond the end of the container to include the neck of the electric bulb—is our preference, we would not limit ourselves to this particular form, as any one of several well known forms of wrappers, binders, or ties may be used.

Having thus described our invention, we claim:

1. A device comprising a single sheet having a hole in the center for the purpose of admitting the neck of an electric light bulb, each of the four corners of said sheet being scored with a series of four lines and designed to fold inward, bringing the four side panels to inclined angles to form a lamp shade.

2. A sheet of dodecagon shape so scored as to form when folded a rectangular box in a combined container and shade; the four corners of the box folding inward to form a cushioned protection for the electric light bulb, the square end section having a hole as described for the purpose of admitting the neck of the electric light bulb to hold it

in ready position for attaching to the electric light socket; the opposite end of the box being open or uncovered.

3. A sheet so scored as to form a rectangular box in a combined container and shade, 70 having one open or uncovered end and one end containing a hole as described to admit the neck of the electric light bulb; cushions formed of three trihedral faces lying within and across the corners of the box and meeting each other around the inner walls of the box to provide a resilient cushion protection for the electric bulb packed therein.

4. A sheet scored to fold into a rectangular box being a combined container and shade, 80 with the square end section having a hole as described, the opposite end of the box being open; the spaces between the rectangular panels being so scored as to form three trihedral faces which lie within and across the 85 corners of the box and meet each other around the inner walls of the box, thereby providing a series of resilient cushions to protect the electric light bulb packed therein; the container with the electric bulb 90 packed therein adapted to be placed and confined within an outside wrapper, for packing, shipping and handling.

5. A unitary device comprising a sheet 95 foldable to form four equal rectangular sides and an end section of a combined container and lamp shade, the square end section having a hole as described, the opposite end of box being open; the spaces between the rectangular panels being so scored as to form 100 in folding three trihedral faces, said faces folding within the corners of the container and being held in contact with the electric light bulb by the outside tie; these same trihedral faces, by removal of container from 105 outside tie, flaring by their own resiliency or aided if necessary by the hand, to form the fluted corners of a lamp shade.

In testimony whereof we affix our signatures.

J. WARRINGTON HAYES.
